UNITED STATES PATENT OFFICE.

ALBERT DROUET, OF COURTENAY, FRANCE, ASSIGNOR TO SOCIÉTÉ ANONYME MARG-
COL, OF MOULINS T/ALLIER, FRANCE, A CORPORATION OF FRANCE.

LOG-SAWING MACHINE.

Application filed September 29, 1924. Serial No. 740,673.

To all whom it may concern:

Be it known that ALBERT DROUET, citizen of the French Republic, residing at Courtenay, Department of Loiret, France, has 5 invented certain new and useful Improvements in Log-Sawing Machines, of which the following is a specification.

This invention relates to log-sawing machines, band-saws, circular saws and other 10 wood-sawing machines.

The lateral displacement of the work-table upon which is suspended the log or piece to be worked is generally obtained in log-sawing machines either by a system of 15 screws and nuts, or by racks and pinions which automatically at each time advance the work-table by a quantity corresponding to the selected thickness of the saw-cut.

These known devices have the disadvantage of being of complicated construction 20 which must be carried out with great precision in order to obtain the desired accuracy in the thickness of the cuts. Moreover they do not allow of varying rapidly 25 the position of the piece of wood suspended on the work-table by claws.

The device forming the object of the present invention is based upon quite another principle. It consists in the fact that the 30 work-table on which is suspended the part to be sawn is mounted on pivoted parallel arms upon the carriage by means of two or more arms which can be clamped or released at will by the operator charged with 35 the working of the saw. The regulation of the thickness of the saw-cut is obtained by means of a guide arranged parallel to the direction of displacement of the carriage and against which the sawn face of the piece 40 of wood comes automatically by the mere effect of inertia, when the carriage starts forward again. By regulating the position of the guide in relation to the saw-blade there is obtained the desired thickness of the 45 cut. It will be readily understood in these conditions how great is the simplification obtained, since the complicated devices ensuring the automatic lateral displacement of the work-table are completely suppressed. 50

There is obtained at the same time the lateral disengagement of the saw, for, as a result of inertia when the carriage starts back again, the piece of wood moves automatically away from the saw-blade. The invention 55 likewise relates to the system of clamp-

ing with rapid locking, which allows the piece of wood held by the clamps to be passed immediately from the position furthest from the blade to the closest position.

The annexed drawing represents diagrammatically, by way of example only, a form of construction of the object of the invention. Upon this drawing:

Figure 1 is an end view of the carriage.

Figure 2 is a plan view. 65

Figure 3 is an elevation of the machine seen from the right side, showing more especially the device for clamping and releasing the arms upon which the work-table is mounted. 70

Figure 4 is a section on a larger scale, along 4—4 of Figure 1, representing the details of the guide. 75

Figure 5 is a section on a larger scale, along 5—5 of Figure 2, showing the device for clamping the arms. 80

Figure 6 is a vertical section of the gripping system with rapid locking. 85

Figure 7 is a transverse section along 7—7 of Figure 6. 90

Figure 8 is an elevation of an extension of the claws. 95

In the example represented, the carriage consists of two frames *a* connected by longitudinal members *a*¹, and runs by means of 85 rollers *a*² upon a track *a*³. Upon the frames *a* are mounted by means of pivots, preferably with ball bearings, equal arms *b* which support the work-table *c*, likewise by means of ball-bearing pivots. The distance between the pivots of the arms upon the carriage and upon the work-table are equal so that the whole forms a jointed parallelogram. The piece of wood *d* to be sawed is suspended on the work-table by means of claws *e* and *f* with rapid locking, of which the description will be given hereafter. 90

Upon each of the arms *b* is fixed a sector *b*¹ which slides in a member *g* integral with the frame *a*; a screw *g*¹ provided at its upper end with a lever *g*² allows of clamping the sector *b*¹ in the member *g* in any position. A spring *g*³ under constant tension is attached on one hand to the lever *g*² and on the other hand to the frame *a*, and tends constantly to clamp the sector *b*¹. The simultaneous clamping of the two sectors is obtained by means of a cable *h* fixed to the levers *g*². This cable passes over a jockey pulley *h*¹ carried by the carriage, then over 100

105

110

- two other jockey pulleys h^2 h^3 mounted in supports fixed to the ground and between which is located a movable pulley h^4 ; the free end of the cable is fixed at h^5 upon the carriage. The movable pulley h^4 is rotatably mounted at the extremity of a lever h^6 keyed on the end of a shaft h^7 arranged perpendicularly to the direction of travel of the carriage in bearings fixed to the ground.
- At the other end of the shaft h^7 is keyed a pedal i arranged within reach of the operator charged with the working of the machine. When the carriage moves, the cable simply runs over the pulleys without causing any displacement of the levers g^2 . But if pressure be applied upon the pedal i , the pulley h^4 falls and exerts upon the cable a pull in the opposite direction to that of the springs g^3 so that the sectors b^1 are released.
- A retaining device constituted by a second pedal j pivoted at j^1 and provided with a hooking lug j^2 , allows of fixing the pedal i in the releasing position when desired. A simple tap upon the pedal j is sufficient to free the pedal i and restore the clamping action.
- In the vicinity of the saw-blade k is arranged the guide consisting of a plate l , the face of which is very slightly inclined to the sawn face of the piece of wood d .
- This plate is mounted upon a rod l^4 which can slide in a supporting member l^2 compressing a spring l^5 engaged between a collar on the rod l^4 at one end and the member l^2 at the other end; upon this member is fixed an arm l^6 carrying at its extremity a vertical plate l^7 provided with a bevel face l^8 intended to facilitate the passage of the wood from the plate l onto the plate l^7 in the movement of the wood toward the saw blade; the lateral surface of this plate parallel to the plane of sawing projects slightly in relation to the face of the plate l . The member l^2 which slides in a frame l^3 is provided, with a rack l^4 gearing with a pinion l^5 keyed upon the shaft of a hand-wheel m . This wheel is provided with a drum m^1 which is marked with divisions and is covered by a casing m^2 integral with the frame l^3 . This casing carries a window m^3 allowing the divisions on the drum m^1 to be seen. An index line is marked in the centre of the window in order to facilitate the reading of the divisions. The plate l can be provided with vertical slots or apertures to allow the escape of sawdust adhering to the wood.

The working of the device is the following:

It will be supposed that the carriage has been returned backwards and that the piece of wood, suspended on the work-table by the claws, has had its face trimmed by a first passage under the saw; the pedal i being retained in the releasing position, when the carriage starts forward again, the piece of

wood d as a result of its inertia, lays itself against the plate l ; the latter has been adjusted beforehand in the desired position by the operator who reads the corresponding division in the window m^3 . The piece of wood slides with its trimmed face upon the plate l^7 exerting a friction which ensures perfect contact of the wood with it and therefore very accurate guiding during the work. The operator disengages the retaining pedal j before the wood arrives in contact with the saw so that the sectors b^1 are held fast by the clamping device. The piece of wood passes beneath the saw and when it has moved past the latter, the operator again engages the pedal i in the releasing position. When the carriage starts back again, the piece of wood d as a result of its inertia moves automatically away from the saw-blade which is thus freed.

Owing to the elastic mounting of the plate l any shock received by this plate is absorbed by the spring l^5 so that the dividing mechanism is completely protected.

The work-gripping system with rapid locking represented on a larger scale in Figures 6 and 7 allows of mounting upon the carriage round or squared pieces of wood. It consists of a dovetail slide or guideway n , in which are slidably fitted members n^1 and n^2 carrying the claws e and f respectively. The upper claw e is raised and lowered by hand; it carries with it in its movements a member p likewise sliding in the guideway; this member p is provided with a screw p^1 which is furnished at its outer end with a lever p^2 and engages at its other end (having the screw-thread removed) in a lodgment formed in the claw-carrying member n^1 . When the lever p^2 is actuated in such a way as to advance the screw p^1 into the member p , the latter tends to move away from the member n^1 so that the whole becomes wedged immediately in the slideway. By undoing the screw p^1 , the wedging action is removed and the claw e becomes free at once.

The operation of the lower claw f is effected by means of a wheel q integral with a screw q^1 which is rotatably mounted in the work-table and is in mesh with a nut formed in the member n^2 .

When it is desired to operate the machine upon pieces of wood of irregular shape, the claws e f may be too short to act properly. In cases of this kind, there may be fitted between the claw-carrying members n^1 n^2 the claw-extension shown in Figure 8.

This device comprises a rod r carrying two claw members s s^1 , the one fixed and the other slidable, the first being intended to fit the screw claw-carrier n^2 and the second the claw-carrier n^1 . For this purpose the member s and the member s^1 are provided with extension claws s^2 , in each of which a hole s^3 is provided for the screw q^1 .

is bored parallel to the rod r . Each hole s^3 is called upon to receive one of the cylindrical lugs t^4 fitted on the confronting faces of the claw carriers n^1 n^2 .

5 The entry to the holes s^3 is milled to a shape facilitating the engagement, which is very rapid.

The lug t corresponding to the sliding member s is formed with a circular groove 10 into which there enters during assembly the tip of the bolt u pushed forward by the spring u^1 so that the said member becomes fast with the claw carrier n^1 , being releasable therefrom when the bolt is withdrawn 15 from its lodgment by pulling the knob u^2 .

Owing to the arrangement of the connections, the extension can be made to pivot around the axis of the lugs in order to vary the orientation and the reach of the claws.

20 It is quite evident that the invention is not limited to the form of construction which has been described and that it can be carried out according to any modification based upon the same principle. Thus the 25 system of locking and releasing the arms of the parallelogram might be different, the clamping and releasing might be obtained automatically at the desired moment by a system of tappets or the like adjustable in 30 position or not, or the guide-plate l might be replaced by horizontal spring blades, the spring l^5 being then suppressed.

What I claim is:

1. A wood sawing machine, comprising, a 35 carriage, a work-table, pivoted parallel arms upon said carriage mounting the work-table to allow it to freely displace itself by inertia, a saw blade arranged parallel to the direction of displacement of the carriage, a 40 gripping device securely holding the piece of wood to be sawn, means for locking the work-table in any desired angular position, and means for adjusting the thickness of the saw-cut.

45 2. A wood sawing machine, comprising, a carriage, a work-table, pivoted parallel arms upon said carriage mounting the work-table to allow it to freely displace itself by inertia, a saw blade arranged parallel to the 50 direction of displacement of the carriage, a gripping device for securely holding the piece of wood to be sawn, members fixed to the arms of the work-table, means for clamping said members at will relatively 55 to the carriage, and means for adjusting the thickness of the saw-cut.

3. A wood sawing machine, comprising, a 60 carriage, a work-table, pivoted parallel arms upon said carriage mounting the work-table to allow it to freely displace itself by inertia, a saw blade arranged parallel to the 65 direction of displacement of the carriage, a gripping device for securely holding the piece of wood to be sawn, members fixed to the arms of the work-table, means for 70

clamping said members at will relatively to the carriage, means for locking and releasing the clamping means at will, and means for adjusting the thickness of the saw-cut.

4. A wood sawing machine, comprising, 70 a carriage, a work-table, pivoted parallel arms upon said carriage mounting the work-table to allow it to freely displace itself by inertia, a saw blade arranged parallel to the direction of displacement of the carriage, 75 a gripping device for securely holding the piece of wood to be sawn, means for locking the work-table in any angular desired position, a work positioning plate arranged adjacent the saw blade and parallel 80 thereto and to the direction of displacement of the carriage, for guiding the face of the piece of wood to be sawn, and means for adjusting the position of the plate relatively to the work-table.

85 5. A wood sawing machine, comprising, a carriage, a work-table, pivoted parallel arms upon said carriage mounting the work-table to allow it to freely displace itself by inertia, a saw blade arranged parallel to the 90 direction of displacement of the carriage, a gripping device for securely holding the piece of wood to be sawn, means for locking the work-table in any angular desired position, a work positioning plate arranged 95 adjacent the saw blade and parallel thereto and to the direction of displacement of the carriage for guiding the face of the piece of wood to be sawn, means for adjusting the position of the plate relatively to the work-table, and means for controlling the adjustment of the work positioning plate.

100 6. A wood sawing machine, comprising, a carriage, a work-table, pivoted parallel arms upon said carriage mounting the work-table to allow it to freely displace itself by inertia, a saw blade arranged parallel to the 105 direction of displacement of the carriage, a gripping device for securely holding the piece of wood to be sawn, means for locking the work-table in any angular desired position, 110 a yieldingly supported work positioning plate arranged adjacent the saw blade and parallel thereto and to the direction of displacement of the carriage for guiding the face of the piece of wood to be sawn, and means for adjusting the position of the plate relatively to the work-table.

115 7. A wood sawing machine, comprising, a carriage, a work-table, pivoted parallel 120 arms upon said carriage mounting the work-table to allow it to freely displace itself by inertia, a saw blade arranged parallel to the direction of displacement of the carriage, a gripping device for securely holding the 125 piece of wood to be sawn, means for locking the work-table in any angular desired position, a yieldingly supported work positioning plate arranged adjacent the saw blade and parallel thereto and to the direc- 130

- tion of displacement of the carriage for guiding the face of the piece of wood to be sawn, and means for adjusting the position of the plate relatively to the work-table and
5 a narrow fixed guide plate, arranged between the work positioning plate and the saw blade and parallel thereto, the plane of the guide plate projecting slightly beyond that of the positioning plate, the edge of
10 the fixed guide plate being bevelled on the side adjacent the work positioning plate.
8. A wood sawing machine, comprising, a carriage, a work-table, pivoted parallel arms upon said carriage mounting the work-table
15 to allow it to freely displace itself by inertia, a saw blade arranged parallel to the

direction of displacement of the carriage, a gripping device for securely holding the piece of wood to be sawn, said device comprising a slideway, a first claw, a nut fixed 20 to the first claw, a screw engaging with the nut, means for actuating the screw and displacing the claw in the slideway, a second claw loosely mounted in the slideway, hand-controlled means for locking the claw in the 25 slideway, means for locking the work-table in any desired angular position, and means for adjusting the thickness of the saw-cut.

In testimony whereof I have signed my name to this specification.

ALBERT DROUET.
